DESIGN FOR A TABLE

Walter C. Ross, Belleville, Ill.

Application December 29, 1945, Serial No. 125,152

Term of patent 14 years

(Cl. D33—14)

To all whom it may concern:

Be it known that I, Walter C. Ross, a citizen of the United States of America, residing in Belleville, in the county of St. Clair, State of Illinois, have invented a new, original, and ornamental Design for a Table, of which the following is a specification, reference being had to the accompanying drawing forming a part thereof.

The single view of the drawing illustrates in perspective a table showing my new design.

I claim:

The ornamental design for a table, as shown.

WALTER C. ROSS.
